UNITED STATES PATENT OFFICE.

JOHN HERRON, OF OLNEY, ILLINOIS, ASSIGNOR OF ONE-THIRD TO
F. T. PHILLIPS, OF SAME PLACE.

MUSIC-LEAF TURNER.

SPECIFICATION forming part of Letters Patent No. 333,519, dated January 5, 1886.

Application filed November 28, 1884. Serial No. 149,043. (No model.)

To all whom it may concern:

Be it known that I, JNO. HERRON, of Olney, in the county of Richland and State of Illinois, have invented certain new and useful Improvements in Music-Leaf Turners; and I do hereby declare the following to be a full, clear, and exact description of the invention, such as will enable others skilled in the art to which it pertains to make and use it, reference being had to the accompanying drawings, which form part of this specification.

My invention relates to an improvement in music-turners; and it consists in the combination of pivoted levers which have their lower ends passed through a slot in the frame, and which have their upper ends connected to endwise-moving rods which are provided with racks, and which racks engage with pinions which turn idly upon a pivotal shaft, and which pinions have connected to them arms provided with suitable clasps for attaching the arms to the leaves of music, as will be more fully described hereinafter.

The object of my invention is to provide an attachment for musical instruments by means of which the player can quickly and readily turn the leaves of the music, either singly or any desired number of them together, and in which the leaves of the music are turned entirely from the top, in contradistinction to the bottom, for the purpose of turning the leaves more quickly and holding them better, and supporting them more perfectly in position.

Figure 1 is a front elevation of an apparatus embodying my invention. Fig. 2 is a rear view of the same. Figs. 3, 4, 5 are detailed views.

A represents a suitable frame or support, which will be of any desired height or width that may be preferred, and which may be provided with the folding wings B, for the purpose of increasing its width, and thus forming a more perfect support for the music. The lower end of this frame may be made perfectly plain, so as to rest upon a piano or other musical instrument; or it may be provided with means, as here shown, for attaching it to a suitable base or support, C. This base or support C is provided with dovetailed projections D, which catch over corresponding projections, E, formed upon the lower end of the base A.

When the projections are made to catch in the dovetailed projections upon the base, the frame is supported in position at a suitable inclination, and thus can be placed upon a table or any other suitable support provided to receive it.

Pivoted upon the back of the frame A are any desired number of operating-rods, F, each one of which has a small handle or projection, G, formed upon its lower end, and which handle extends through the slot H, formed in the lower end of the base. The lower ends of the levers are held in position by a suitable cross-piece, I, as shown in Fig. 2, for the purpose of preventing them from having any unnecessary play or vibration. To the upper end of each one of these levers is attached an endwise-moving rod or bar, K, each one of which has a series of teeth or a rack, J, formed upon its inner edge. These racks or teeth J engage with corresponding pinions, L, which turn loosely upon the pivotal rod N. To each pinion is connected an arm, O, which has connected to its outer end the vertical piece P. This vertical piece P has its upper end turned inward, so as to catch over and center upon the pivotal rod, while to its lower end is attached an arm, Q, which is provided with the spring-clasps R, for catching over the top edges of the different sheets of music. When any one of the levers is moved by means of the handle upon its lower end, the endwise-moving rod attached to the upper end of the lever causes a corresponding pinion on the pivotal rod to revolve, and thus turn a corresponding leaf of music. If the levers are not moved in their regular order, two or more or all of the leaves of music can be turned at the same time.

Over the top and front of the endwise-moving rods, the pinions, and the bars, which are connected directly to the pinions, is placed a suitable semicircular frame or covering of any kind, so as to conceal these bars, but which frame or covering has a curved slot through its lower end, so that the vertical pieces which are connected to the arms on the pinions can freely sweep through a portion of a circle. By thus covering the different bars they are not only protected from dust and dirt, but from accidental injury in every way.

It will be seen that attachment is made to

the leaves of music at their top edges, in contradistinction to their lower edges, for the purpose of turning the leaves not only more quickly, but of holding them more perfectly 5 in position.

- When it is desired to support a book or music without attaching the leaves to the turning devices, the support X is attached to the frame A by means of the hooks Y, as shown. 10 This support is made from several pieces, which are hinged together, so that the support can be folded into a small compass.

To the different parts of the support are secured projections Z, for the purpose of keeping the book or leaves of music from slipping 15 off the support.

Having thus described my invention, I claim—

1. In a music-leaf turner, the combination of 20 the frame having a slot through its lower end, the handles which project through the slot, the

levers pivoted on the back of the frame, the rack-bars connected to the upper ends of the levers, pinions L on the rod N, arms O, and the vertical pieces P, having the arms and 25 holding devices on their lower ends, substantially as shown.

2. The combination of the frame A, for supporting the music, the levers pivoted upon its back and provided with handles at their lower 30 ends, the rack-bars J K, the pinions L, rod N, arms O, and projections P, which extend upward from the arms and are centered at their upper ends upon the rod N, and which have the arms Q and spring holding devices R secured to 35 their lower ends, substantially as described.

In testimony whereof I affix my signature in presence of two witnesses.

JOHN HERRON.
